UNITED STATES PATENT OFFICE.

EFFA T. BARSTOW, OF TACOMA, WASHINGTON.

HOLDER FOR IRONING-BOARD COVERS.

1,112,350.

Specification of Letters Patent.

Patented Sept. 29, 1914.

Application filed April 23, 1914. Serial No. 833,945.

To all whom it may concern:

Be it known that I, **EFFA T. BARSTOW**, a citizen of the United States, residing at Tacoma, in the county of Pierce and State 5 of Washington, have invented certain new and useful Improvements in Holders for Ironing-Board Covers; and I do declare the following to be a full, clear, and exact description of the invention, such as will enable others skilled in the art to which it appertains to make and use the same.

This invention relates to improvements in holders for ironing board covers and the primary object of the invention is to provide a holder of the character described which may be simply and cheaply constructed and which will be strong and efficient in operation.

A secondary object is to provide a device 20 of this character which may be readily folded when not in use.

With the above and other objects in view, the invention resides in certain novel features of construction and combination herein described and claimed and shown in the drawings wherein:

Figure 1 is a bottom plan view of an ironing board showing the application of my improved fastener; Fig. 2 is a top plan view 30 of the fastener removed; Fig. 3 is a transverse section on the line 3—3 of Fig. 1; and Fig. 4 is a top plan view of the holder in folded position.

In the accompanying drawings, I have 35 shown my improved holder as comprising longitudinal cloth gripping jaws 1, slotted links 2 pivoted to said jaws, and fastening means 3 for a purpose to appear. The jaws 1 are preferably formed of flat strips of 40 sheet metal bent substantially upon themselves throughout their lengths to provide lower flanges 4 and upper flanges 5, the latter being provided with teeth 6 which are adapted to bite into the opposite sides of the 45 ironing cloths placed over the board B. The links 2 are slotted as at 7 throughout the major part of their lengths and are pivotally connected at 8 to the lower flanges 4 of the jaws 1, the inner ends of the links 2 car-

ried by one jaw 1 overlapping the links carried by the opposite jaw, and adapted to be secured in position by the fastening elements 3 which are here shown in the form of bolts 9 having the squared portions 19' of their shanks slidably mounted in the slots 7 of one 50 series of the links 2, while the remaining portions of said shanks project through the slots of the other series of links, and are provided with thumb nuts 10.

In the operation of the device, the ironing 60 blanket and sheet are stretched over the ironing board B and their free edges are brought toward each other beneath said board in a well-known manner. The teeth 6 of the jaws 5 are then forced into said meeting edges and the two jaws 1 are then forced toward each other at one end and the thumb nut 10 at said end is tightened to retain them in this position. The other end of the jaws 1 may then be forced together and similarly 65 locked, after which the central links may be fastened in the same manner.

By constructing the device as above described, and as shown in the drawings, the operation of application will be rendered 70 very simple and when the device is not in use, the jaws 1 may be moved toward each other and the links 2 will assume the approximate positions shown in Fig. 4.

From the foregoing description, taken in 75 connection with the accompanying drawings, the construction and operation of the device will be readily understood without requiring a more extended explanation.

Having thus described my invention, what 80 I claim as new and desire to secure by Letters-Patent is:

1. A device of the character described, comprising a pair of longitudinal jaws having upper and lower inwardly extending 85 flanges connected along their outer edges, the upper flanges being of less width than the lower, teeth along the inner edges of the upper flanges, slotted links pivoted to said lower flanges and extending inwardly into 90 overlapping engagement, bolts depending through the slots of said links and thumb nuts on said bolts.

2. A device of the character described comprising a pair of spaced longitudinal toothed jaws, inwardly extending links pivoted to said jaws and lying in overlapping engagement with one another, and clamping means for locking said links against movement.

In testimony whereof I have hereunto set my hand in presence of two subscribing witnesses.

EFFA T. BARSTOW.
